UNITED STATES PATENT OFFICE.

CHARLES FREBORG, OF DE KALB, ILLINOIS, ASSIGNEE TO MELVILLE CLARK, OF CHICAGO,
ILLINOIS.

ADJUSTABLE SUPPORT FOR MUSIC-ROLLS FOR AUTOMATIC MUSICAL INSTRUMENTS.

No. 888,395.

Specification of Letters Patent.

Patented May 19, 1908.

Application filed March 17, 1906. Serial No. 306,527.

To all whom it may concern:

Be it known that I, CHARLES FREBORG, a citizen of the United States, residing at De Kalb, in the county of Dekalb and State of Illinois, have invented new and useful Improvements in Adjustable Supports for Music-Rolls for Automatic Musical Instruments, of which the following is a specification, reference being had to the accompanying drawings, forming a part thereof.

The purpose of this invention is to provide in an automatic player for musical instruments means of supporting the music roll, which is adapted to support rolls of different lengths, such as are provided for operating a greater or less portion of the manual; that is to say, from 88 notes, for which the longest rolls are adapted, to 58 notes, which is the ordinary compass of the shorter rolls.

It consists of the features of construction set out in the specification and claims and shown in the drawings for extending the supports toward each other and securing them at the several positions which correspond to the different lengths of the rolls.

In the drawings:—Figure 1 is a partly sectional plan view of the portion of an automatic player concerned in this invention with the immediately adjacent parts, the cheeks 30 being broken away and shown in section at the axes of the music-roll-supporting spindles. Fig. 2 is an axial section on a larger scale than Fig. 1 of the centering spindle and its support. Fig. 3 is a section at the line 35 3—3 on Fig. 2. Fig. 4 is a section at the line 4—4 on Fig. 3. Fig. 5 is a partly sectional side elevation of the driving spindle, same being shown engaged with the head of a roll, section being made axially through the bearing and the outer sleeve of said spindle, and the head of the roll being broken away and shown in axial section with its socket engaged with the square protruding driving terminal of the spindle. Fig. 6 is a section 45 at the line 6—6 on Fig. 5, showing the driving-spindle engaged with a protruding flanged terminal of the roll.

In the drawings, the supporting frame for the roll bearings and tracker is represented by the cheeks, 1 and 2, and the connecting base, 3.

The tracker board is shown at 4.

5 is the take-up roll which is provided with adjustable flanges, 5^a, which may be moved

along the roll to accommodate perforated sheets of different widths.

6 represents the left-hand end plate of the motor frame in which are the bearings for the driving spindles of both music roll and take-up roll. From this plate, the bearing bosses 6^a project into the right-hand cheek, 1, the boss, 6^a, being thus provided for the driving spindle of the music roll. This driving spindle is made in three telescoping sleeves, 7, 8 and 9. The sleeve, 7, has rigid with it the pinion, 7^a, through which power is communicated to rotate the spindle. The sleeve, 8, within the sleeve, 7, has a slot, 8^a, with an offset portion, 8^b, for engagement with a stud, 7^b, which projects inwardly from the sleeve, 7, said slot and stud coöperating to form a "bayonet lock" connection between the two sleeves which permits the sleeve, 8, to be adjusted within the sleeve, 7, the length of the slot and locked at protruded position, as shown in Fig. 5. The sleeve, 8, has another slot, 8^c, in the outer half of its length, and near the outer extremity it is provided with an inwardly projecting pin or stud, 8^d. The sleeve, 9, has a longitudinal furrow, 9^a, with which the pin, 8^d, engages to guide the sleeve, 9, in its longitudinal telescoping movement and there secured within the sleeve, 9, a spring, 10, having a portion, 10^a, which protrudes out through a suitably located slot, 9^b, for engagement with the slot, 8^c, of the sleeve, 8, to lock the sleeve, 9, at its most protruded position with respect to the sleeve, 8. To the end of the sleeve, 9, there is secured a terminal chuck, 11. This chuck has an axial aperture to receive a pintle of the roll to be driven and is slotted across the axial aperture, as seen at 11^a, to engage the wings, 12^a, of such pintle, 12. Within the axial aperture of the chuck, 11, and the corresponding axial bore of the sleeve, 9, there is provided a plunger, 13, which is forced outward by a spring, 14, lodged behind it in the sleeve, 9, and stopped against a shoulder, 9^c. A thumb screw, 15, set in through the side of the chuck enters a seat formed on the side of the plunger by cutting away the same as seen at 13^c, and serves as a stop to limit the protrusion of the plunger under the action of the spring and also as a set screw to hold the plunger retracted when desired. The plunger has a square terminal, 13^d, which at the outermost position protrudes from the chuck and is adapted to

engage a square socket in a roll so provided, as seen in Fig. 5.

When the three sleeves, 9, 8 and 7, are telescoped within each other, the terminal 5 chuck is withdrawn toward the cheek to a position adapted to accommodate the longest roll, and in this position, as in all other positions which may be adjusted, it is to engage and drive either a roll having a socket such as 10 shown in Fig. 5, in which case the square terminal, 13^a, affects the driving engagement, or a roll having a protruding driving pintle, 12, as shown in Fig. 6, in which case the engagement is made by the wings, 12^a, engaging 15 in the slots, 11^a, of the chuck, the plunger being thrust back into the cavity of the sleeve, 9, and preferably, though not necessarily, held thus retracted by the thumb screw, 15, operating as a set screw. For a 20 roll of the next shorter length, as 65 notes, the sleeve, 9, is drawn outward in the sleeve, 8, the latter being left at its inner position in the sleeve, 7, stopped at the bottom of the cavity of the latter sleeve where a diaphragm 25 or plug, 16, is provided for that purpose, the sleeve, 9, being stopped against inward movement in the sleeve, 8, by the engagement of the bend, 10^a, of the spring, 10, in the slot, 8^a, of the sleeve, 8. For the shortest roll, 58 30 notes, the sleeve, 9, being left protruded from the sleeve, 8, as above described, the sleeve, 8, is drawn outward in the sleeve, 7, to the limit of the slot, 8^a, and locked with the pin, 7^b, by a slight rotation, as may be understood from 35 Fig. 5. Preferably, the end thrust of the spindle is taken by a stop bracket, 17, mounted on the motor frame plate, 6, and projecting past the end of the spindle, and to reduce the friction of such end thrust the actual 40 bearing is formed by a steel ball, 18, which is lodged in a socket on the outer side of a diaphragm or plug, 16, and bears against a clip, 19, which is arranged to slide on to the end of the bracket, 17, as may be understood from 45 comparison of Figs. 1 and 5.

20 is a centering spindle for the opposite end of the music roll. It is mounted for sliding through a bearing flange or bracket, 21, which is secured to the inner side of the 50 left-hand cheek, 2, and is provided with a protruding boss, 21^a, of sufficient length to adequately guide the spindle 20, and hold it accurately aligned with the driving spindle while permitting it to slide through it for the 55 adjustments hereinafter described. On the back side of the bearing flange, 21, there is mounted a latch, 22, pivoted at one side of the bearing of the spindle and extending across to the opposite side, and provided with 60 a spring, 23, tending to hold its nose or spindle - engaging projection, 22^a, inward toward the axis. The spindle, 20, is provided with three annular grooves, 20^a, 20^b and 20^c, at such positions and distances apart 65 that when the latch, 22, is engaged with the

groove, 20^a, the spindle is in proper position to accommodate the longest roll. When the latch is engaged with the groove, 20^b, the spindle is protruded to the position for engaging the roll of the next shorter length, 65 notes, and when the latch is engaged with the groove, 20^c, the spindle is at proper position for engaging the shorter roll, 58 notes. 70

25 is the terminal for engaging and centering the rolls. It is lodged in an axial bore, 20^d, in the inner end of the spindle and thrust outward by a spring, 24, lodged therein, being stopped by a pin, 26, which takes into the space between the two shoulders formed by reducing the pin in diameter at 25^a, for a distance equal to the yielding movement at any time to be required of the terminal, 25. This terminal is adapted to engage and center, either the roll which has a socket or the roll which has a protruding pintle, the 80 reduced end, 25^c, entering the socket of a socketed roll, and the pintle of a roll so provided entering the socket, 25^d, in the end of the reduced terminal, 25^c. For operating the latch, 22, it is provided with a finger 90 piece, 27, which projects through a slot, 21^b, in the flange, 21, so as to be readily accessible at the inner side of the cheek, 2.

I claim:

1. In an automatic musical instrument or 95 player in combination with fixed supports for the two ends of the music roll, movable supports mounted on the fixed supports and adjustable toward and from each other to accommodate rolls of different lengths, and means for securing said adjustable supports at a limited plural number of definite respectively corresponding positions within their range of adjustability.

2. In an automatic musical instrument or 100 player, in combination with fixed supports for the two ends of the music roll; a driving element supported by one of said fixed supports and a centering element supported by the other, said driving and centering elements being adjustable with respect to their 105 said fixed supports toward and from each other to accommodate rolls of different lengths, and means for securing said elements at a definite plurality of respectively 110 corresponding positions within their range of adjustability.

3. In an automatic musical instrument or 115 player, a driving spindle for a music roll consisting of a plurality of telescoped sections 120 which are adjustable relatively for protruding the driving terminal more or less; means for stopping them one upon another at a plurality of relative positions within the range of their telescopic adjustability, in 125 combination with a centering spindle for the roll, and a support for the same on which it is longitudinally movable, and releasable means for stopping and locking it at a definite plurality of positions corresponding respectively 130

to the several positions of the driving terminal of the driving spindle.

4. In an automatic musical instrument or player, a centering spindle for the music roll; 5 a centering terminal mounted on said spindle and a spring for yieldingly protruding it relatively to the spindle; a fixed bearing through which the spindle extends and in which it is longitudinally movable, and releasable means 10 for stopping and locking it at a definite plurality of positions within its range of movability.

5. In an automatic musical instrument or player, a driving spindle for a music roll 15 having a driving chuck provided with an axial aperture formed at the end for driving engagement with a non - circular body; a plunger lodged in such aperture and adapted to be withdrawn thereinto back of the end 20 thereof, and a spring tending to protrude it, such plunger having its protruded end non-

circular in cross-section for driving engagement with a correspondingly socketed body.

6. In an automatic musical instrument, a driving spindle for a music roll having a 25 driving chuck provided with an axial aperture and having at the end radial slots leading from such aperture; a plunger having a terminal which is polygonal in cross-section lodged in such axial aperture adapted to be 30 thrust thereinto back of the end and to protrude said terminal therefrom; a spring tending to protrude it, and a set screw for securing it in retracted position.

In testimony whereof, I have hereunto set 35 my hand at De Kalb, Illinois, this 13th day of Mar., 1906.
